CLAIM

The ornamental design for a puzzle or similar article, substantially as shown and described.

DESCRIPTION

FIG. 1 is a side elevational view of a puzzle or similar article showing our new design;

FIG. 2 is a side elevational view thereof as viewed from the opposite side;

FIG. 3 is a top plan view thereof;

FIG. 4 is a bottom plan view thereof; and

FIG. 5 is an exploded view showing the layers into which the puzzle is divided, and the central pin which locks the sections together in the form shown in FIGS. 1 – 4.

FIG. 1

FIG. 2

FIG. 3

FIG. 4

FIG. 5
